[57] **CLAIM**

The ornamental design for a electrical conductor wire feeding tube for fire wall lead-in, as shown.

DESCRIPTION

FIG. 1 is a perspective view of an electrical conductor wire feeding tube for fire wall lead-in showing our new design;

FIG. 2 is a perspective view from the opposite side thereof;

FIG. 3 is a side elevational view thereof.

FIG. 1

FIG. 2

FIG. 3
